UNITED STATES PATENT OFFICE

151,759

DESIGN FOR A CASING FOR SERVICE
STATION DISPENSING APPARATUS

Arthur Paul Hoppe, Salisbury, Md.

Application November 14, 1946, Serial No. 134,793

Term of patent 14 years

(Cl. D52—2)

To all whom it may concern:

Be it known that I, Arthur Paul Hoppe, a citizen of the United States, residing at Salisbury, in the county of Wicomico and State of Maryland, have invented a new, original, and ornamental Design for a Casing for Service Station Dispensing Apparatus, of which the following is a specification, reference being had to the accompanying drawing, forming a part thereof.

In the drawing:

Fig. 1 is a front elevation of a casing for service station dispensing apparatus, showing my new design.

Fig. 2 is a side elevation of the casing.

Fig. 3 is a contour section on the line 3—3 of Fig. 1.

The rear elevation of the casing is the same in appearance as the front.

The dominant features of my design reside in the portion shown in full lines.

I claim:

The ornamental design for a casing for service station dispensing apparatus, as shown and described.

ARTHUR PAUL HOPPE.
